TOBACCO CURING SYSTEM

John E. Thomas, Goldston, N. C., assignor of one-half to King Roofing and Manufacturing Co., Sanford, N. C., a firm

Application December 21, 1949, Serial No. 134,194

1 Claim. (Cl. 237—53)

1

This invention relates to the art of tobacco curing and more especially to an improved hot air distributing system for use in tobacco curing barns.

It is an object of this invention to provide an improved hot air distributing system for tobacco barns having a centrally located heating plant therein, such as a coal burning furnace, and comprising a plurality of radially extending pipes communicating with the heating chamber of the heating plant and extending to remote areas of the tobacco barn and the ends of all or at least a plurality of these pipes being connected to a common pipe, which, in turn, has branch pipes connected thereto and extending outwardly through the wall of the tobacco barn to thus discharge any of the products of combustion from the heating chamber to the exterior of the barn and to provide extended pipe surface areas for radiating the heat and to thus distribute the heat from the heating chamber evenly throughout the barn.

The object heretofore stated and including the means for discharging the gases of the products of combustion exteriorly of the barn are an important feature of the present invention since heretofore, many of the heating systems and particularly those systems which communicated directly with the chamber in which combustion took place, included pipes which were open at their ends remote from the combustion chamber and thus discharged the products of combustion directly into the barn. This has had a harmful effect on the tobacco being cured, especially where the heat was produced through the combustion of hard coal and the like since most tobacco is damp when it is placed in the tobacco barn and will sweat during the drying process and, in the instance of anthracite coal, one of the products of combustion is sulphur which when mixed with the moisture on the tobacco leaves created an acid condition which would burn parts of the tobacco leaves resulting in an inferior leaf.

Some of the objects of the invention having been stated, other objects will appear as the description proceeds when taken in connection with the accompanying drawings in which—

Figure 1 is a sectional plan view of a tobacco curing barn showing a centrally located heating plant therein and the pipes comprising the improved hot air distributing system connected thereto;

Figure 2 is an enlarged vertical section taken substantially along the line 2—2 in Figure 1 and showing a form of heating plant or furnace which

may be used in conjunction with the hot air distributing system of the present invention and also showing a portion of a coal introducing stoker and parts of the hot air distributing pipes associated therewith;

Figure 3 is an enlarged elevation looking substantially along the left-hand side of Figure 1 but with parts of the near wall omitted so as to show the heating system in elevation disposed within the tobacco barn;

Figure 4 is a schematic elevation showing the furnace and two of the radially extending pipes connected thereto and is taken looking substantially along the line 4—4 in Figure 1 the remaining pipes are omitted for purposes of clarity;

Figure 5 is an elevation similar to Figure 4 and showing a portion of the tobacco barn with parts broken away and also showing the discharge pipes for the products of combustion extending through the walls of the barn and is taken looking substantially along the line 5—5 in Figure 1.

Referring more specifically to the drawings, the numeral 10 broadly designates a tobacco barn having a floor 11, side walls 12 and 13 and front 25 and rear walls 14 and 15 respectively. This particular barn has a gable roof 16 provided with a longitudinally extending opening at the ridge thereof and having a suitable ventilating means generally designated at 17 thereon. As is well known, the tobacco barn is provided with a plurality of horizontally disposed tier poles 20, only two of which are shown in Figure 3. The structure of the barn may vary considerably from that described, the barn shown in the drawings merely being shown by way of illustration since the invention resides entirely in a hot air distributing system to be presently described.

There are many types of heating plants or furnaces wherein the products of combustion are 40 discharged directly into the heating chamber of the furnace. Such a type of furnace is shown in Figure 2 and is indicated broadly at 25. This particular furnace 25 is a coal burning furnace having a fire pot 26 disposed therein to which coal is directed from a hopper 27 which is a part of a stoker broadly designated at 30. This stoker may be of any desired construction and includes a driven screw conveyor 31 and a blower, not shown, disposed within a housing 32, both of 45 which are driven through suitable gearing, not shown, which is, in turn, driven by an electric motor 34 having electric wires 35 and 36 extending therefrom to a suitable source of electrical energy not shown.

The furnace 25 comprises a jacket 37 having a

55

liner wall of refractory material 48 on the inside thereof the upper edge of which defines a heating chamber 41 the upper end of which is closed by a top 42 of the jacket 37 and this top 42 being covered with a suitable heat insulation material 43. The jacket 37 is circular, although it may be polygonal if so desired, and has a plurality of radially spaced openings 44 therein in which the inner ends of a plurality of radially extending pipes 45 to 54, inclusive, of a heat distributing system broadly designated at 56 are mounted.

Each of the pipes 45 to 49 has a down-turned pipe elbow 57 connected to the ends thereof remote from the furnace 25 and which are connected to a common pipe 60 which extends in spaced parallel relation to the left-hand side wall 12 and also extends for substantially half the width of the barn 10 in spaced relation to the front and rear walls 14 and 15 respectively. The common pipe 60 has a pair of discharge pipes 61 and 62 connected thereto and spaced substantially half-way between the pipes 46 and 47 and 48 respectively.

The radially extending pipes 50 to 54, inclusive, also have suitable down-turned pipe elbows 65 on the outer ends thereof which are connected to a common pipe 66 and this pipe 66 also has a pair of spaced discharged pipes 70 and 71 connected thereto and being spaced each side of the elbow 65 to which the pipe 52 is connected. The common pipes 60 and 66 may be endless and may be joined together if so desired, these pipes being shown as two separate pipes in the drawings in order to provide a space therebetween in which the hopper 27 may be disposed and to also provide a space for access to the furnace 25 by an operator. It is evident that the common pipes 60 and 66 are each made up of a plurality of pipe sections and suitable pipe T's are provided for connecting these pipe sections to one another as well as to the pipes branching therefrom, however, a detailed description of the pipe sections and the pipe T's is deemed unnecessary since this construction is well known to the art. Each of the discharge pipes 61, 62, 70 and 71 has a down-turned elbow 73 on the outer end thereof to prevent moisture and any foreign matter from falling into the ends of the discharge pipes 61, 62, 70 and 71.

It is thus seen that I have not only provided an improved heat distributing system for tobacco barns wherein a greater surface area of the pipes is exposed so as to radiate and distribute heat uniformly throughout the interior of the tobacco barn, but I have also provided means for discharging the gases or products of combustion from the furnace through said pipes and through suitable discharge pipes to the exterior of the tobacco barn, these discharge pipes being positioned so remotely from the centrally

located heating plant or furnace as to cause very little of the heat to be discharged exteriorly of the barn along with the products of combustion since substantially all of the heat from the heating chamber 41 will have dissipated through the walls of the radially extending pipes 45 to 54, inclusive, and the common pipes 60 and 66 by the time the products of combustion are discharged into the atmosphere. The down-turned elbows 57 and 65 on the ends of the radially extending pipes 45 to 54, inclusive, assist in preventing the heated air from being discharged through the discharge pipes since the air will tend to rise through radiation and convection until cooled.

In the drawings and specification there has been set forth a preferred embodiment of the invention, and although specific terms are employed, they are used in a generic and descriptive sense only, and not for purposes of limitation, the scope of the invention being defined in the claim.

I claim:

25 A tobacco curing system for tobacco barns having a furnace therein provided with a combustion chamber and a heating chamber and said furnace having a plurality of radially spaced openings therein communicating with the heating chamber, said system comprising a plurality of radially extending pipes connected at one of their ends to the furnace and communicating with the openings in the heating chamber, a down-turned pipe elbow on the outer ends of each of the radially extending pipes, a common 30 pipe connected to the open end of each of the down-turned pipe elbows, at least one discharge pipe connected to the common pipe and extending radially therefrom relative to the furnace and through the adjacent wall of the barn to thus discharge the products of combustion from the furnace exteriorly of the barn and also to provide extended pipe surface areas for radiating and distributing heat uniformly throughout the barn.

45 JOHN E. THOMAS.
